UNITED STATES PATENT OFFICE.

JOHN P. HARTSOE, OF WELDON, NORTH CAROLINA.

CONE-PUNCTURING MACHINE.

Application filed December 17, 1924. Serial No. 756,590.

This invention is an apparatus for puncturing paper cones which are employed for winding yarn where the yarn is dyed on the cone by the use of a vacuum or compressed air. Means have been heretofore provided for puncturing such paper cones but, so far as I am aware, these prior devices punctured the cone outwardly from its interior and burs or rough spots were thereby formed upon the exterior of the cone so that the yarn did not unwind cleanly and frequently broke so that there was a great waste. It is the object of my invention to provide a puncturing mechanism by the use of which the cones will be punctured inwardly from their exteriors and the outer surface of the cone will be left just as smooth as before it was punctured. This object I attain in the use of such an apparatus as is illustrated in the accompanying drawing, and the invention consists in certain novel features which will be hereinafter first fully described and then particularly pointed out in the claims.

25 In the drawing:—

Figure 1 is an elevation of a machine embodying my invention, and

Fig. 2 is an enlarged longitudinal section of the puncturing devices showing a cone in 30 position to be punctured.

In the drawing, the reference numeral 1 indicates a bench or rigid supporting frame upon which is secured a post or pedestal 2 having a horizontally disposed cylinder 3 mounted upon its upper end. The reference numeral 4 indicates a tank for compressed air or other motive fluid, such as steam, which is kept supplied with the fluid under pressure in any convenient manner, as by 35 connection with a steam boiler or with an air compressor. From the tank or reservoir 4, a pipe 5 extends along the table or supporting frame 1 and leads into a controlling valve 6 of any known or approved form 40 whereby the flow of the fluid may be controlled. From the valve 6, pipes 7 and 8 extend to the cylinder 3 and communicate with the interior thereof through the heads or ends of the same, as will be readily understood. Within the cylinder is mounted a reciprocating piston 9, the piston rod 10 of which extends through a packing box 11 on one end of the cylinder and is slidably supported and guided in a bearing 12 which is 45 erected upon the frame or table 1. The free end of the piston rod beyond the bearing 12

is equipped with a head 13 which may be a collar having an annular groove 14 in its outer circumference and is disposed within a hub 15 which is secured upon the reduced 60 end 16 of the bearing 12 by set screws 17 inserted radially through one end of the hub 4 and bearing against the said reduced extension, as clearly shown in Fig. 2. The hub 15 is constructed with longitudinal slots 65 18 between its ends and at intervals around its entire circumference. At the sides of these slots are outwardly projecting lugs or ridges 19 having transverse notches formed in their outer edges to receive a stout rod 70 20 which encircles the entire hub and is secured in the said notches by clamping bolts 21. This rod 20 constitutes a fulcrum for the puncturing arms 22 which are provided at their inner or pivoted ends with inwardly 75 projecting fingers 23 passing through the slots 18 and engaging in the annular groove 14 of the head 13. The outer free working members of these arms are provided on their inner opposed sides with spurs 24 which are 80 adapted to readily pierce and pass through the paper cone 25 which is supported upon a mandrel 26 carried by the hub 15. As shown most clearly in Fig. 2, the outer or free end of the hub 15 is constructed with an 85 annular shoulder 27 and is tapered, as at 28, beyond said shoulder so that the conical mandrel 26 may fit closely about the tapered end of the hub and abut the shoulder 27, being secured to the hub by set screws 29 in 90 inserted through its end portion into the hub, as clearly shown. The mandrel is preferably an integral metal casting having teeth 30 formed upon its exterior, the said teeth 95 projecting toward the hub so that the cone 95 may be very readily slipped over the outer end of the mandrel and held thereon while being punctured. At intervals around the mandrel longitudinal slots 31 are formed through the wall of the same, and these slots 100 are so arranged as to be in alinement with the puncturing spurs or points 24 of the respective puncturing arms.

The use of the device will, it is thought, be readily understood. It is evident that 105 the flow of compressed air, steam or other motive fluid may be directed into either end of the cylinder 3 by adjusting the valve 6 and the operation of the machine is thus easily controlled by the workman. Assuming the parts to be in the position shown in the drawing, the valve 6 is set so that the mo-

tive fluid will pass through the pipe 7 into the cylinder and drive the piston toward the right-hand end of the cylinder in Fig. 1, this direction of movement being indicated by the arrow in Fig. 2. The head 13 upon the piston rod will thus be caused to move toward the reduced extension 16 and will cause the fingers 23 to swing in the same direction, the lever arms being, consequently, rocked about the fulcrum rod 20 so that the spurs 24 will be forced inwardly through the shell or wall of the cone 25. When the cone has been punctured, the valve 6 is reversed or set so that the motive fluid may exhaust from the left-hand end of the cylinder and will be admitted through the right-hand end thereof so that the piston will be given a reverse movement and the parts returned to the positions illustrated. The cone may then be easily removed and a new cone fitted upon the mandrel to be punctured. It will be readily noted that with my apparatus the cone is firmly supported while being punctured and the holes formed by the puncturing spurs will be clean and sharply defined and the slight bur which is produced by the puncturing act will be formed upon the inner surface of the cone where it cannot affect the winding or the unwinding of the yarn. While I have shown and described my device as being operated by fluid pressure, it will be understood that it may be operated mechanically or by hand without involving any departure from the spirit or scope of the invention as the same is defined in the following claims.

Having thus described the invention, I claim:

40. 1. Means for puncturing cones comprising

ing a slotted tapered mandrel to fit within and support the cone, puncturing arms mounted adjacent one end of the mandrel to extend longitudinally over the mandrel and a cone supported thereon, and means for actuating said arms whereby portions of the arms will pass inwardly through the wall of the cone toward the mandrel to puncture the cone.

2. Means for puncturing cones comprising a tapered mandrel to fit within and support a cone and having slots formed through its wall at intervals around its circumference, rocking puncturing arms mounted adjacent one end of the mandrel and disposed about the same and provided on their inner edges with puncturing points presented to the slots in the mandrel and to a cone supported on the mandrel, and means for rocking said arms whereby to cause the puncturing points to pass inwardly through the wall of the cone into the slots in the mandrel.

3. Means for puncturing cones comprising a hub provided with longitudinal slots in its circumferential extent, a tapered mandrel secured to the end of the hub and projecting therefrom in axial alignment therewith, puncturing arms fulcrumed upon the hub and disposed about the mandrel and provided with fingers extending inwardly through the slots in the hub, a head housed within the hub and engaged with the free ends of said fingers, and means for reciprocating said head whereby to rock the puncturing arms toward and from the mandrel.

In testimony whereof I affix my signature.

JOHN P. HARTSOE. [L.S.]
